UNITED STATES PATENT OFFICE.

WILLIAM COOPER, OF GEORGETOWN, COLORADO.

AUTOMATIC EMERGENCY-BRAKE.

No. 849,599.

Specification of Letters Patent.

Patented April 9, 1907.

Application filed December 18, 1906. Serial No. 348,406.

To all whom it may concern:

Be it known that I, WILLIAM COOPER, a citizen of the United States, and residing in the city of Georgetown, in the county of Clear Creek and State of Colorado, have invented or discovered new and useful Improvements in Automatic Emergency-Brakes, of which the following is a specification.

My invention consists in certain new and useful improvements in safety devices for hoisting and other power-driven mechanism. Frequently in the use of such mechanism an accident has happened to the engineer or other operator in charge whereby he is incapacitated and control is lost, thereby causing great loss of life or property. Such an accident is particularly frequent in the case of a descending bucket or cage in mining operations, the contents thereof being dashed to the foot of the shaft.

I have produced a device whereby the operation of such mechanism is promptly and automatically stopped in the case of such an emergency, which device more particularly consists of a member in the general form of a chock or wedge block normally out of engagement with the operating mechanism, but adapted to automatically engage and block the same in case of accident to the engineer. In the accompanying drawings, Figure 1 is a side elevation of a conventional form of hoisting mechanism fitted with my invention adapted to engage the cable-spool. Fig. 2 is a plan view of the same, and Fig. 3 is a reduced partial elevation showing the member arranged to engage one of the crank-disks.

The following is a detailed description of the drawings.

1 is the cable-spool, which in lowering the cage or bucket is supposed in this case to revolve in the direction of the arrow in Fig. 1. 2 is the braking-surface upon which the band-brake 3 may be applied by means of hand-lever 4, provided with the usual locking-quadrant 5. 6 is the main shaft, from which said cable-spool is revolved by means of the usual gears 7 and 7^a and a suitable clutch mechanism. (Not shown.)

8 are the crank-disks on the ends of shaft 6, which are operatively connected by connecting-rods and pistons to cylinders 9 9 in the usual manner.

10 is the steam-pipe, provided with the usual throttle 11 and branch pipes 12 12, running to the cylinders.

13 is the counterbalance-weight device to

normally hold band-brake 3 out of close engagement with braking-surface 2 of spool 1.

14 14 are pivot-standards suitably secured to proper foundations under the floor of the engine-room.

15 is a cross-shaft journaled in boxings 16 16, secured to standards 14 14.

17 is a beam or lever rigidly attached intermediate of its ends to shaft 15. On the extremity of beam 17 adjacent to the hoist is secured a small platform 18 of sufficient size to permit the operator to stand thereon and operate the throttle 11. On the other extremity of said beam is mounted a weight 19, adjustable by being slid along said beam and securable in any desired position, the said weight being so adjusted as to be overbalanced by the weight of the operator on platform 18.

20 is a crank-arm rigidly secured to one end of shaft 15.

21 is a chock-block or wedge member, preferably of the general contour indicated and of any suitable material, such as metal or wood. Said member is adapted to slide in guides 22 22, attached to fixed support 23, which is preferably inclined, as shown. Said block is normally out of engagement with the annular face 24 of the cable-spool 1, but on being drawn forward becomes wedged between its support 23 and said face 24, thus bringing said spool into a full stop and preventing the fall of the cage, bucket, skip, or car controlled by the cable.

25 is a standard to which is pivoted lever 26 intermediate of its ends.

27 is a connecting-rod pivotally attached to member 21 and at its other end to one end of lever 26.

28 is a second connecting-rod pivoted at one end to lever 26 and at the other end to crank-arm 20.

It is evident that should the operator step or fall from platform 18 the weight 19 would draw down the other end of beam 17, thus forcing the connecting-rod 28 toward the hoist, and by the action of lever 26 drawing the connecting-rod 27 forward, thus drawing the member 21 along support 23 into close engagement with face 24 of the cable-spool. The rotation of the spool in the direction of the arrow would assist in this wedging action, and the cable-spool would be brought to a prompt and complete stop and the accident prevented.

In Fig. 3 I show the member 21 applied to

the periphery of crank-disk 8, thus in case of emergency blocking the revolution of the crank-disk, and with it the cable-spool connected therewith.

5 It is evident from the above that the construction illustrated may be varied by applying the member 21 to any revolving element in the hoist whose blocking will stop the cable-spool.

10 I have shown my invention applied to a conventional form of hoisting mechanism; but it is evident that it is equally applicable to any form of hoisting or power mechanism, whether driven by steam, compressed air, 15 electricity, or any other power.

I prefer to arrange my platform 18 so that when depressed it will assume the general level of the floor of the engine-room, and so locate it that the throttle will be within convenient reach of the operator while standing 20 on said platform.

What I desire to claim is—

1. In power mechanism, a fixed member, a rotatable member, a third member adapted 25 to be wedged between said members, operative means for drawing said third member into said engagement and means whereby the weight of the operator counterbalances said operative means, substantially as and 30 for the purpose set forth

2. In hoists, a rotatable member, a fixed support, a member slideable on said fixed sup-

port and adapted to be brought into wedging engagement between said rotatable member and said fixed support, means for drawing 35 said wedging member into operative position and means whereby the weight of the operator counterbalances said first-mentioned means, substantially as and for the purpose set forth.

3. In hoists, a rotatable member, a fixed member, a third member adapted to be brought into wedging engagement between said rotatable member and said fixed member, a weighted lever adapted to operate said 45 wedge member and means whereby the weight of the operator counterbalances said weighted lever, substantially as and for the purpose set forth.

4. In hoists, a rotatable member, a fixed 50 incline member, a third member adapted to be drawn up said incline member into wedging engagement with said rotatable member, a weighted device adapted to operate said wedge member and means whereby the 55 weight of the operator counterbalances said weighted device, substantially as and for the purpose set forth.

Signed at Pittsburgh, Pennsylvania, this 13th day of December, 1906.

WILLIAM COOPER.
